CENTRIFUGAL PUMP

Donald S. Higgins, Balboa, Calif., assignor to Shellmaker Inc., Los Angeles, Calif., a corporation of California

Application June 4, 1952, Serial No. 291,684

2 Claims. (Cl. 103—103)

This invention relates generally to the fluid pump art and more particularly to centrifugal pumps. Specifically, the invention is concerned with a centrifugal pump designed particularly for use in a dredge operative to draw or suck mud, sand and other sediment from a harbor or river bed and force the same through a duct leading to a collecting scow, a river bank or other point of use or disposal.

Dredges of the suction type currently used for dredging harbors, channels and rivers usually include an inlet pipe which is lowered to the river or harbor bottom and frequently provided with a steel grating or head and a rotary cutter or drill. The mud or silt is drawn upwardly through the inlet pipe or duct through the action of a centrifugal pump of large capacity located on the deck of the dredge, the suction pipe being connected to the suction or inlet part of the pump. As the pump is operated, the mud or like material is drawn upwardly from the bottom of the waterway and discharged through a duct to be conveyed thereby to the point of use or disposal.

As is well known by those versed in the art of dredging, centrifugal pumps designed for this purpose have the very serious disadvantage that their closely fitting and relatively movable components are continuously subjected to abrasion caused by minute particles of sand or other material which invariably lodge between the closely fitting faces of the pump housing and the impeller. Such abrasive action of the sand has the deleterious effect of causing scoring or other wear between the parts and this eventually results in loss of efficiency of the pump. That is to say, when the wear occurs in the surfaces normally separating the high pressure discharge side from the low pressure inlet side, a very serious loss of discharge pressure ensues, due to the fact that the high pressure water is forcibly returned to the inlet side of the pump. This loss of volumetric flow is further aggravated and constantly multiplied due to the fact that the water in returning to the inlet side of the pump provides a carrier for additional sand particles which are floated into the space between the closely fitting surfaces to increase the abrasive action. This deficiency of dredge pumps is, therefore, a very serious one which results in inefficiency and eventual inoperativeness of the pumping unit. In actual practice, efficient pump operation can be expected over a very short period of time, it being frequently necessary to discontinue operation of the pump after a period of but a few hours and to overhaul the pump by installing new liners therein. Such interruption in the operation obviously results in loss of time and this is reflected in the over-all cost of the dredging. While new parts for the pump may be kept available for installation, or the dredge be provided with an extra or auxiliary pump, the upkeep of such pumps requires the constant attention of skilled mechanics.

Various expedients have been proposed for alleviating the condition discussed above, that is, for reducing wear between the relatively movable pump surfaces, one such

2

means being in the nature of hardened steel wear plates or rings and while these may make for a higher degree of efficiency, they do not prolong the operative life of the pump to any appreciable extent. As a general rule, therefore, the problem has been considerably a practically unsolvable one and for this reason the condition continues to be tolerated by dredge operators.

It is therefore an important object of this invention to alleviate the deficiencies and disadvantages of dredging and like centrifugal pumps used for pumping sand or other abrasive material by providing a centrifugal pump having means embodied therein for practically eliminating wear between the pump impeller and the adjacent wall of the housing, so as to render the pump highly efficient almost indefinitely. This object is best attained by providing means for producing and maintaining fluid pressure in the clearance space between the impeller shroud and the casing wall adjacent the impeller eye. In accordance with the invention, said fluid pressure is in excess of that produced in the volute and discharge end of the pump so that the water pressurized in the volute, and the sand particles suspended therein, is effectively excluded from the space referred to above and prevented from returning to the inlet or eye side of the impeller to be repumped thereby. Thus, by this means, the presence of abrasive particles in said clearance space is positively avoided and the pump is capable of efficient operation over long periods of time without requiring overhauling, rebuilding or renewal of its components.

Another object of the invention is to provide a centrifugal pump of the character referred to in which the wear-resisting means comprises a resilient ring disposed at the interior of the front casing wall and provided with a pair of concentric beads or fins on its inner face for engaging the corresponding face of the front shroud of the impeller. The beads define, with the shroud and casing wall, a circular channel or pressure chamber into which fluid is introduced under pressure exceeding that of the fluid discharged by the pump. The fluid pressure existing in the annular sealing chamber thus provides, in effect, a buffer or fluid partition between the high and low pressure sides of the pump to positively guard against reverse flow of fluid from the discharge side to the inlet side of the impeller.

Another object is to provide a pump of the class indicated in which the annular beads of the resilient sealing ring are lightly compressible against the shroud of the impeller so as to produce a substantially fluid tight seal. A related object is to provide means for adjusting the ring axially toward and away from the impeller so as to attain the proper degree of compression of the sealing beads thereagainst. In accordance with the invention, this means consists of a plurality of push bolts on the pump casing and engageable against a metal reinforcing ring formed integrally with the resilient sealing ring.

Another object is to provide means for introducing the pressure sealing liquid into the annular chamber formed by the beads of the resilient ring, this means comprising a plurality of tubular studs screwed into threaded holes in the metal reinforcing ring in alignment with holes formed transversely in the resilient ring and in communication with the annular chamber, the outer ends of the studs having connected thereto flexible tubes through which the pressurizing liquid flows from a suitable auxiliary pump.

A further object of the invention is to provide in a centrifugal pump a combined sealing and wear-reducing means which is extremely simple in construction and economical to produce, one which is convenient to install in existing as well as in new pumps, and one which is positive in action and requires no special servicing.

Further objects will appear from the following description and from the drawing, which is intended for the purpose of illustration only, and in which:

Fig. 1 is an axial sectional view through a centrifugal dredge pump, showing the improved sealing and wear-reducing means embodied therein;

Fig. 2 is a cross-sectional view, taken on line 2—2, of Fig. 1;

Fig. 3 is an enlarged fragmentary sectional view through the pressure-sealing means of the invention; and

Fig. 4 is a perspective view of the adjustable impeller sealing ring and associated parts.

Referring to the drawing in detail, the centrifugal pump illustrated, by way of example, includes a base 5 and a casing 6 supported thereby. The casing 6 has a front wall 7, a back wall 8 and a scroll-like central portion or volute 9 provided with a tangential discharge mouth 10 to which may be connected a duct 11 leading to a point where the pumped material is delivered. As shown, the front wall 7 is connected to the central portion 9 by means of bolts 12 in the usual manner. In pumps of the type employed for pumping fluids and relatively solid matter which are apt to corrode and abrade the inner surfaces, the inner surfaces of the pump casing are provided with liners, such as those shown at 13, 14, and 15 in Fig. 1.

A drive shaft 20 is journaled in bearings 21 on the base 5 and extends into the casing 6 through a hole 22 in the back wall 8, a suitable stuffing box 23 being employed for sealing this portion of the pump. Connected to the inner end of the shaft within the casing 6 is an impeller 25, of any conventional type, said impeller having a front shroud 26 and an inlet opening or eye 27. Secured to the forward face of the shroud 26 is a wear ring 28. The casing 6 is provided with a tubular inlet fitting 29 through which the material to be pumped is directed into the center of the impeller, said fitting being connected to the inlet or suction pipe 20 of the dredge.

The inlet opening in the front wall of the casing 6 is made larger in diameter than the internal diameter of the inlet tube 29, thus providing an annular recess 32 for receiving a resilient ring 33. As shown, the ring 33 may be substantially square in cross-sectional shape and provided at one side with a metal backing element or reinforcing ring 34, this element being preferably formed as an insert in the molded ring 33 and provided with a plurality of threaded holes 35 registering with holes 36 in the ring 33.

At its opposite side, the resilient ring 33 is formed with a pair of concentric, annular, compressible ribs or beads 37 and 38. While these beads may be of various cross-sectional shapes, it has been found advantageous to make them semicircular in form so as to provide substantially point contact between their extremities and the wear ring 28 of the impeller 25. Means, to be presently described, are provided for adjusting the ring 33 toward the wear ring 28 so as to compress the beads 37 and 38 lightly thereagainst and, since it is desirable that the inner bead 37 be compressed to a slightly greater degree, this bead is made to extend to a slightly greater distance from the inner face of the ring 33 than the outer bead 38. It is to be noted by reference to Fig. 3 that the beads define with the wear ring 28 an annular chamber 40.

The resilient ring 33 is forced toward the wear ring 28 by means of push-bolts 42 which are screwed through holes in the flange 43 of the inlet fitting 29 with their inner ends engaging the metal reinforcing ring 34.

During operation of the dredge pump, water is introduced into the pressure sealing chamber 40 by way of the aligned holes 35 and 36, the pressure of the water being in excess of the fluid pressure developed by the pump in the volute at the discharge end thereof. Screwed into the holes 35 are tubular studs 45 which pass through apertures 46 in the flange 43, check nuts 47 being screwed

onto the studs and set up against the flange. Connected to the outer projecting ends of the tubular studs 45 are flexible tubes 48, these tubes leading from a suitable fluid pressure manifold supplied with pressurized water from a suitable pump, these last-named parts not being shown in the drawing.

During operation of the dredge, the impeller 25 is rotated with the shaft 20 within the casing 6 to draw the sand-laden water upwardly from the harbor- or river-bottom through the suction pipe 20, the dredged material being forced radially outwardly into the volute by the rotating impeller blades. Thus, fluid pressure is created within the casing 6 and the discharge 10. Also, during operation of the pump, sealing water is introduced into the annular channel or chamber 40 by way of the tubes 48, tubular studs 45 and the holes 36, the pressure of this water being greater than that of the fluid pressure developed within the pump. Consequently, any tendency of the pressure fluid in the casing 6 to escape into the low pressure inlet passage, through the space normally existing between the wear ring 28 and the inner surface of the front casing wall 7, 13, is effectively prevented. The present fluid pressure sealing means thus guards against sand particles entering said space to cause scoring and abrasion of the adjacent surfaces of the wear ring and the front wall of the casing which occur in conventional dredge pumps due to the lack of adequate sealing means for the purpose. Thus, by the present invention the efficiency of the pump is increased materially and wear, which usually occurs between the impeller and the casing, is practically eliminated so that the pump may be operated almost indefinitely without resurfacing, relining or replacing these closely fitting parts. Since the present ingenious sealing means avoids wear and frequent servicing of the pump, the over-all upkeep cost of the dredge is effectively minimized and this is an important consideration.

It is to be noted that the resilient sealing ring 33 normally is urged toward the wear ring 28 with a force which at least lightly compresses the fins or beads 37 and 38 thereagainst to seal the sides of the pressure chamber 40. By such sealing, escape of the pressure sealing fluid from the chamber 40 into either the inlet or discharge sides of the pump is minimized. A gentle flow of the sealing water past the beads may, however, be desirable for the purpose of flushing away minute particles of sand which might tend to lodge against the outer surfaces of the beads, and for reducing wear of the beads. As previously explained, such adjustment of the sealing ring 33 toward and away from the impeller is effected by means of the push-bolts 42. When the beads eventually become worn, the ring 33 may be easily replaced by simply removing the cover-like front wall 7 and the sealing ring carried thereby, after which the studs 45 are withdrawn to release the ring. A new ring 33 is then installed by reversing the above procedure and the pump is thus reconditioned for continued dredging service with a minimum of expended time, effort and expense involved.

In accordance with the patent statutes, I have disclosed herein what I consider to represent the best embodiment of the invention. It is to be understood, however, that various modifications might be made in the construction and arrangement of the dredge pump within the spirit of the invention. Consequently, I do not wish to be limited in this respect, but desire to be accorded the full scope of the appended claims.

I claim as my invention:

1. A centrifugal pump for use particularly in pumping liquid containing solid particles, comprising a casing having a forward wall, an axial inlet port and a substantially radial discharge port; an impeller rotatable within said casing and having a shroud disposed adjacent, but spaced from, said wall; a resilient sealing ring slidably mounted in a recess in a side of said casing; means operative to adjust said ring toward and away from said impeller; said

ring having a pair of concentric, annular, compressible beads on its side facing said impeller, said beads having substantially semi-circular ends engageable with said shroud and defining therewith a fluid pressure chamber located in the annular clearance space between said shroud and said wall; and means connected to said sealing ring and communicating with its said chamber for introducing fluid into said chamber at a pressure in excess of the fluid pressure developed within said casing by said impeller so as to prevent passage of the fluid from the pressure side of said casing to the inlet port thereof by way of said annular space, said fluid introducing means including a metal reinforcing ring embedded in said sealing ring and having at least one threaded hole therein registering with at least one transverse hole in the ring communicating with said pressure chamber; and a tubular stud screwed into said threaded hole for conducting pressure fluid to the chamber.

2. A centrifugal pump for use particularly in pumping liquid containing solid particles, comprising: a casing 20 having a forward wall, an axial inlet port and a substantially radial discharge port; an impeller rotatable within said casing and having a shroud disposed adjacent, but spaced from, said wall; a resilient sealing ring slidably mounted in a recess in a side of said casing; means operative to adjust said ring toward and away from said impeller, said ring having a pair of concentric, annular, com-

pressible beads on its side facing said impeller, said beads having substantially semi-circular ends engageable with said shroud and defining therewith a fluid pressure chamber located in the annular clearance space between said shroud and said wall; and means connected to said sealing ring and communicating with its said chamber for introducing fluid into said chamber at a pressure in excess of the fluid pressure developed within said casing by said impeller so as to prevent passage of the fluid from the pressure side of said casing to the inlet port thereof by way of said annular space, said fluid introducing means including a metal reinforcing ring embedded in said resilient sealing ring and having a plurality of threaded holes therein registering with a plurality of holes in the ring in communication with said pressure chamber; and a plurality of tubular studs, each screwed into a said threaded hole and adapted to conduct pressure fluid to said chamber.
